Primary Examiner — Elizabeth J Oswecki*(74) Attorney, Agent, or Firm* — Sughrue Mion, PLLC;
Richard C. Turner**CLAIM**The ornamental design for a semiconductor device, as
shown and described.**DESCRIPTION**

FIG. 1 is a front, top and right side perspective view of a semiconductor device showing our new design;
FIG. 2 is a rear, top, and left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a front, top and right side perspective view thereof,
shown in a used condition attached to a mount shown in
broken lines; and,
FIG. 10 is another front elevational view thereof, attached to
a mount shown in broken lines.
The broken lines shown in the drawings represent portions
of the semiconductor device that form no part of the claimed
design.
